(Cl. D72—1)

To all whom it may concern:

Be it known that I, Frank H. Wyatt, a citizen of the United States and residing at Long Beach, county of Los Angeles, State of California, have invented a new, original, and ornamental Design for a Guard Ring for Protecting Ground Lights or the like, of which the following is a specification, reference being had to the accompanying drawing, forming part thereof, in which:

Fig. 1 is a perspective view of a guard ring for protecting ground lights or the like, showing my new design;

Fig. 2 is a top plan view thereof, and

Fig. 3 is a side elevational view.

I claim:

The ornamental design for a guard ring for protecting ground lights or the like, substantially as shown.

FRANK H. WYATT.
